UNITED STATES PATENT OFFICE.

JULIUS K. LUX, OF WASHINGTON, DISTRICT OF COLUMBIA.

OPERATING MEANS FOR CIRCUIT-CONTROLLING DEVICES.

966,457.

Specification of Letters Patent.

Patented Aug. 9, 1910.

Application filed August 25, 1906. Serial No. 332,026.

To all whom it may concern:

Be it known that I, JULIUS K. LUX, a citizen of the United States, residing at Washington, in the District of Columbia, have 5 invented certain new and useful Improvements in Operating Means for Circuit-Controlling Devices, of which the following is a specification.

My invention relates particularly to means 10 for indicating the positions of the movable contact and to operating means or handles for operating circuit controlling devices; objects of the invention are to provide an operating and indicating means which operating means may be moved or turned in 15 one rotary direction from its normal operative position without operating the movable contact, or injuriously affecting the operation of the device or the parts thereof to insure against undue stresses to parts of the 20 device, to provide indicating or operating means or both of these, which may be interchangeably applied to devices of a given class, so that in their operative position they 25 will uniformly have a predetermined position relative to the movable contact thereby to indicate the open or other conditions of the circuits, said means being exterior to the cover for indicating the position of the 30 movable contact the more conspicuously and unfailingly, while permitting the complete inclosure of the device so as to exclude dust, moisture, insects and the like. To provide in combination with the herein-described 35 features a means for easily removing and applying the said cover, indicating means, and operating means with a limited number of separately detachable parts. To provide an indicating means that will not impart 40 weight or momentum to the snap actuated parts of a switch.

Other objects of my invention will appear hereinafter.

Figure 1, is a detail sectional view of one 45 form of indicator and operating handle, and related parts, embodying my invention. Fig. 2, is a plan view of the blank from which the indicator is formed; and showing a ferrule G⁸ which is secured to the said 50 blank so as to be flush with the top of the blank and to project downwardly therefrom as shown in Fig. 1. Fig. 3, is a plan view of a spring piece struck up from sheet metal which spring piece is interposed between 55 the indicator and the cover to hold the latter part in position on the base of the

switch. Fig. 4, is a view of the extremity of the positioning means E² for positioning the indicator relatively to the movable contact. Fig. 5 shows two views of the positioning 60 means F taken at right angles to each other.

Referring to the drawings in detail, E indicates the operating handle the top plan view of which may be of circular or of other suitable form. The said handle is formed 65 of insulation and has a metal center part to impart strength and receive the screw thread. The handle has a circular groove near its base portion into which groove, portions of the herein-described indicating 70 means are inserted so as to secure the handle and indicator together while leaving the said parts free to rotate relatively each to the other. By reason of this connection the indicator may be rotated freely in either direction to come into a predetermined position as the handle is being screwed down on the spindle.

G⁴ is the means for indicating the position of the movable contact. The said indicator is struck up out of sheet metal and has two lugs G⁷ formed from the central part and bent downwardly as shown in Figs. 1 and 2, to provide anchorage in the insulating material which forms a herein-described 80 positioning means E². The ferrule G⁸ is secured to the part G⁴ to reinforce the insulation part E². The said indicator G⁴ has three lugs G⁶ integral therewith, which lugs are bent upwardly and caused to engage the 85 handle in the aforesaid circular groove thereof so as to form the above-described connection.

E² is a positioning means for positioning the indicator relatively to the movable contact. The said positioning means E² is molded about portions of the indicator so as to insulate the spindle G³ and other electrically charged parts from the said indicator. The said positioning means is cylindical in form and has a wedge-shaped or inclined extremity as shown in dotted lines in Fig. 1, and more clearly at E² of Figs. 4 and 5.

G³ is the spindle usual in devices of this 105 class, the same being broken away for the sake of brevity.

F, is a positioning means secured to the spindle so as to coöperate with the detachable positioning means E². The said positioning means F, has six inclined bearing 110 surfaces. Four of the said inclined bearing

surfaces are designed to direct the pointed end of E^2 into the final home position as shown in Fig. 1, and also in the diagram at the right hand side of Fig. 5. The said 5 parts are so designed that upon screwing the handle down on the spindle the indicator cannot lodge or catch or come to rest except in predetermined positions in which positions it will unfailingly indicate the position of the movable contact. The apexes of 10 the said four directing inclines are clearly shown on F , in Fig. 5.

N , is a section of the cover which usually incloses devices of this class.

15. N^1 is a character (as "on" or "off") to indicate the position of the movable contact or other condition of the circuit.

The part N^5 is a spring secured to the cover to press against the indicator or handle 20 in such manner as to hold the cover snugly to the base.

To remove the operating means from the switch the tongues G^6 are bent downwardly and the handle part E , is merely unscrewed 25 from the spindle, —the part G^4-E^2 need not turn at all.

To apply the operating means it is merely necessary to screw the handle part E , onto the spindle, as the handle is screwed down 30 the positioning means E^2 strikes the positioning means F , and for example it may strike at the apex of F , the edges of E and F , are so positioned and conformed that they will not dwell in engagement but will 35 slide off of the apex and the part E , being screwed farther down the positioning means E^2 slides down the compound inclines of the part F until it jams home; at the same time the handle E will jam on the screw-thread 40 and be in driving engagement with the spindle G^3 .

I claim:

1. In an operating means for a rotary snap switch, a handle detachable from the 45 switch, means whereby the said handle is normally rotatable in one direction without operating the said switch, indicating means detachable from the switch, and means on one of the said detachable parts for positioning the indicator, said positioning means comprising members having coacting inclines for positioning the said indicator relatively to a coöperative part on the switch.

2. In an operating means for a rotary 55 snap switch, a handle detachable from the switch, means whereby the said handle is normally rotatable in one direction without operating the said switch, indicating means detachable from the switch, means on one 60 of the said detachable parts for positioning the indicator, coöperative positioning means

on the switch, said coöperative positioning means comprising members having coacting inclines for positioning the indicator relatively to the switch.

3. In an operating means for a rotary snap switch, a handle detachable from the switch, means whereby the said handle is normally rotatable in one direction without operating the said switch, indicating means, means including coacting inclines for positioning the indicator, said operating handle being rotatable relatively to the said positioning means.

4. In an operating means for a rotary snap switch, coaxial positioning members having coacting interfitting inclines for positioning an indicating means, an indicating means secured to one of said members, operating means for rotating the positioning 80 members and indicating means including a handle and connections between the handle and the other positioning member whereby the positioning members are held in a predetermined position relative to the switch.

5. In an operating means for a rotary snap switch, coaxial positioning members having coacting inclined faces for positioning an indicating means, an indicating means secured to one of said members, operating means for rotating the positioning members and indicating means including a handle and connections between the handle and the other positioning member whereby the positioning members are held in a predetermined position relative to the switch, 90 said handle being rotatable in one direction independently of the positioning members and indicating means.

6. In an operating means for a rotary snap switch, a handle for operating the switch, an indicating member rotatable in one direction with the handle, and means comprising coacting inclines for positioning the indicator relatively to the switch.

7. In an operating means for a rotary snap switch, a handle detachable from the switch, means whereby the said handle is normally rotatable in one direction without operating the said switch, indicating means, positioning means for the said indicator, said positioning means comprising a part with a depression having inclined sides to position the indicator relatively to the said switch.

Signed at Washington D. C. this 25th day of August 1906.

JULIUS K. LUX.
